UNITED STATES PATENT OFFICE.

THOMAS TROUSDALE HARRISON, OF AUBREY, KANSAS.

SULKY-PLOW.

SPECIFICATION forming part of Letters Patent No. 292,804, dated January 22, 1884.

Application filed October 22, 1883. (No model.)

To all whom it may concern:

Be it known that I, THOMAS TROUSDALE HARRISON, of Aubrey, in the county of Johnson and State of Kansas, have invented certain new and useful Improvements in Sulky-Plows, of which the following is a full, clear, and exact description.

Reference is to be had to the accompanying drawings, forming part of this specification, in which similar letters of reference indicate corresponding parts in all the figures.

Figure 1, Sheet 1, is a plan view of my improved sulky-plow. Fig. 2, Sheet 2, is a side elevation of the same, the land-wheel being removed. Fig. 3, Sheet 2, is a front elevation of the same, the tongue being shown in section, and part being broken away.

The object of this invention is to improve the construction of the sulky-plows for which Letters Patent Nos. 218,734, 232,268, 255,977, and 264,692 were granted to me, respectively, August 19, 1879, September 14, 1880, April 4, 1882, and September 19, 1882, in such a manner as to adapt the plows to turn a square corner in passing around a land without its being necessary to raise the said plows out of the ground.

The invention consists in a sulky-plow constructed with the movable part of its tongue connected by a lever and an eyebolt with the crank-arm of the rod carrying the crank-axle of the furrow-wheel, whereby the lateral movement of the said movable part of the tongue will turn the said wheel laterally, and adapt the machine to turn the corner of a land without having the plow taken out of the ground, as will be hereinafter fully described and claimed.

A is a cross-bar, to the lower side of the middle part of which is attached the middle part of the axle B. The end parts of the axle B are bent downward at right angles, and then outward at right angles, to bring their ends below and at a suitable distance from the ends of the cross-bar A. C is the land-wheel, the crank-axle D of which is attached to the lower end of a rod, E. The rod E passes up through the end of the cross-bar A, and is kept from dropping away from the said cross-bar by a pin passed through the upper end of the said rod, or by other suitable means. The upward movement of the rod E through the

cross-bar A is limited by the block F, through which the said rod passes, and which slides in a slotted or U-shaped hanger, G, attached to the cross-bar A near its end, and to the end of the axle B. The upward movement of the sliding block F within the hanger G is regulated by the crank-screw H, which passes down through a screw-hole in the cross-bar A and rests against the upper side of the said block F, so that the height of the landside end of the cross-bar A, and consequently the depth to which the plow enters the ground, can be regulated by turning the crank-screw H up or down.

To the upright parts of the axle B, near their lower ends, are hinged, by bolts or rivets, the arms of the crank-bar I, to the middle part of which is designed to be clamped the rear part of the plow-beam. One of the arms of the crank-bar I is extended forward and bent upward to form a lever, J, for operating the crank-bar I to raise the plow out of and lower it to the ground.

To the lever J is attached the end of a short chain, J', the other end of which is provided with a ring or large link, to be passed over the hook J'', attached to the cross-bar A, to lock the lever J and crank-bar I in place, and thus hold the plow in the ground. The lever J is provided with an arm, K, to serve as a foot-rest, so that the plowman can raise and lower the plow with his feet. The forward end of the plow-beam passes through the slotted or U-shaped hanger L, the upper end of which is bolted to the cross-bar M. The cross-bar M is slotted longitudinally to receive the fastening-bolt, so that the forward end of the plow-beam can be adjusted laterally, to cause the plow to cut a wider or a narrower furrow.

To the hanger L is pivoted a crank-foot lever, N, to rest upon the forward end of the plow-beam, so that the driver can operate the said lever with his foot, to hold the said forward end of the plow-beam down, to cause the plow to enter the ground, and to hold it in the ground in plowing hard soil. The landside end of the cross-bar M is attached to the lower end of the bar O, the upper end of which is attached to the cross-bar A. The other end of the cross-bar M is attached to the lower end of the bar P, the upper end of which is attached to the rear or stationary part Q of

the tongue. The cross-bar M is further secured in place by being attached at its ends to the braces R, the rear ends of which are attached to the upright parts of the axle B, near their lower ends. The forward ends of the braces R are attached to the stationary part Q of the tongue near the forward end of the said part. The stationary part Q of the tongue is bolted or clamped at or near its rear end to the cross-bar A.

S is the movable part of the tongue, which is pivoted to the stationary part Q by a bolt, T, passing through the said parts Q S. The two parts Q S of the tongue can be secured to each other by two or more bolts when a stiff tongue is required.

To the stationary part Q of the tongue, in front and rear of the pivoting-bolt T, are attached bars U, having upwardly-projecting ends, the said stop-bars being so arranged that the movable part S of the tongue cannot be swung to the right beyond the vertical plane of the said stationary part Q, but can be swung to the left through an angle of forty-five degrees, more or less.

V is the furrow-wheel, the crank-axle W of which is placed beneath the end of the axle B, and is attached to the lower end of the rod X. The rod X passes up through holes in the ends of the axle B and cross-bar A, and has a forwardly-projecting crank-arm, Y, formed upon or attached to its end.

To the crank-arm Y is secured the rear end of a lever, Z, by a bolt, a, and a bolt or set-screw, b. The bolt a passes through holes in the rear end of the lever Z, and in the crank-arm Y, several holes being formed in the said crank-arm to receive the said bolt a, so that the lever Z can be adjusted forward or back, as may be desired. The set-screw b passes through a keeper, c, formed upon the end of the crank-arm Y, and rests against the lever Z, so as to clamp the said lever against the said crank-arm. If desired, the keeper c can be omitted and a cross-slot formed in the end of the crank-arm Y, to receive the screw or bolt b, to secure the lever Z in place. With this construction, by loosening the screw or bolt b, the crank-arm Y can be adjusted to set the forward part of the wheel V in or out, and cause the plow to take or leave land, and thus cut a wider or narrower furrow. The forward part of the lever Z is rounded to pass through the eye of an eyebolt, b, secured to the movable part S of the tongue, so that the said lever Z will be operated by the movements of the said movable part S of the tongue. The crank-axle D of the land-wheel

C is placed in the rear of the end of the axle B, and the crank-axle W of the furrow-wheel V is placed in front of the end of the said axle B, so that the said wheels can be conveniently turned laterally in the proper directions. With this construction, when the team is turned at the corner of the land the movable part S of the tongue takes the position shown in dotted lines in Fig. 1, and operates the lever Z and the crank-arm Y, to cause the furrow-wheel V to take the position shown also in dotted lines in Fig. 1. As the team continues to turn, the furrow-wheel V rolls around the corner of the land into the cross-furrow at the same time the rear part of the land-wheel C swings outward, and the said wheel rolls to the rearward, the machine turning upon the plow as a pivot. Then, as the team moves forward in a straight line the various parts of the machine take their normal positions, and the plow moves on in the new direction without having been taken out of the ground.

I am aware that it is not broadly new to journal a wheel upon a swiveled post with a crank-arm upon the swiveled post connected to the tongue, so that the movement of the tongue will govern the course of the wheel.

Having thus described my invention, what I claim as new, and desire to secure by Letters Patent, is—

1. A sulky-plow constructed with the movable part S of the tongue connected with the furrow-wheel by a lever, Z, adjustably secured to a crank-arm, Y, which is attached to or forms part of the swiveled rod X, in combination with the furrow-wheel V, directly operated by said rod X, substantially as set forth.

2. In a sulky-plow, the combination, with the movable part S of the tongue, and the crank-arm Y of the rod carrying the crank-axle of the furrow-wheel, of the lever Z and the eyebolt d, substantially as herein shown and described, whereby the lateral movement of the said movable part of the tongue is made to turn the said furrow-wheel laterally, as set forth.

3. The movable portion S of the tongue, in combination with the stop-bars U, attached to the stationary part Q of the tongue, whereby lateral movement of the part S is prevented in one direction and limited in the opposite direction, substantially as set forth.

THOMAS TROUSDALE HARRISON.
